HEAT EXCHANGERS FOR VAPORIZING LIQUID REFRIGERANT

Herman W. Kleist, Hollywood, Ill., assignor to Dole Refrigerating Company, Chicago, Ill., a corporation of Illinois

Application March 7, 1955, Serial No. 492,435

7 Claims. (Cl. 62—3)

My invention relates to an improvement in refrigerating means, and has for one purpose to provide improved means for controlling the flow of volatile refrigerant from or to a compressor.

Another purpose is to provide means for controlling the temperature of the refrigerant as supplied to the condenser from the compressor.

Another purpose is to provide control means for controlling the flow of refrigerant from the compressor to the condenser and receiver which render valving or restriction of flow unnecessary.

Another purpose is to provide means effective to compensate for variation in outside ambient temperature, when a flow of volatile refrigerant is subjected to such variations.

Other purposes will appear from time to time in the course of the specification and claims.

The present application is a continuation-in-part of my copending application Serial No. 443,759, filed in the United States Patent Office on July 16, 1954, now Patent No. 2,775,683 of Dec. 2, 1956, for "Heat Exchangers for Vaporizing Liquid Refrigerant."

I illustrate my invention more or less diagrammatically in the accompanying drawings wherein:

Figure 1 is a diagrammatic illustration of an embodiment of my invention;

Figure 2 is an axial section through a heat exchanger indicated in Figure 1; and

Figure 3 is a section on the slide 3—3 of Figure 2.

Like parts are indicated by like symbols throughout the specification and drawings.

Referring to the drawings, 1 generally indicates a compressor in a refrigerating cycle in which, for example, a volatile refrigerant is employed. 2 indicates a suction return pipe extending from any suitable evaporator or evaporators, not herein shown, to the suction or inlet side of the compressor 1. 3 indicates any suitable condenser connected by a pipe 4 to any suitable receiver 5. 6 indicates a duct or pipe from the discharge or pressure side of the compressor 1 to the intake of the condenser 3. A indicates a heat exchange unit in the pipe 6 which will later be described in detail. 7 indicates a delivery pipe extending to any suitable evaporator or evaporators, not shown.

It will be understood that, as an example of my invention, I have illustrated part of a conventional refrigerating cycle in which a volatile refrigerant is delivered as a hot gas from the pressure side of a compressor, such as the compressor 1, is condensed to a hot liquid, still under pressure, in any suitable condensing means, such as my condenser 3, and is thereafter delivered, under pressure, as a liquid, along any suitable delivery line to whatever evaporating means are employed. The volatile refrigerant is evaporated in the evaporator in response to a drop in pressure, which may be obtained in any suitable way, or by any suitable means, not herein shown and not of itself forming part of my invention. I illustrate my

invention as applied to the problem of controlling the temperature of a volatile refrigerant as it is delivered by a compressor to a condenser and receiver. Where the refrigerator, or any part of the refrigerating cycle, is subjected to outside, unheated air, the variations in the outside or ambient temperature create problems. For example, the minimum outdoors ambient temperature in parts of the United States may vary as much as 100° F. or more from the maximum outside ambient temperature.

10 Such a fluctuation of temperature, or even a smaller fluctuation, creates problems affecting the flow of the hot gas from the compressor to the condenser. In the past, attempts have been made to control the resultant pressure fluctuations by valving or restricting the flow of hot gas from the compressor to the condenser. Any such valving or restricting presents practical problems, and has disadvantages into which I need not go in detail.

By my invention, I maintain regulation of flow by keeping the refrigerant at a generally constant temperature, regardless of changes in ambient temperature. I may do this by maintaining adequate heat exchange means in the line of flow of the refrigerant from the compressor to the condenser and by thermostatically controlling such means. As an example of such means I illustrate the unit

15 A in Figure 1, which is shown in greater detail in Figures 2 and 3. In the form shown in Figure 2, I illustrate a heat exchange casing, in the form of an outer shell or cylinder 10, having end closures 11 and 12. The duct 6 delivers refrigerant, as at 6a, through the end 11 of the cylinder 10, and the refrigerant is constrained to a tortuous and extended path, for example, by the spiral or helical vane 13. Refrigerant, after passing through the elongated passage thus formed, escapes, as at 6b, and flows toward the condenser.

20 30 35 While I do not wish to limit myself to any specific heat exchange means, except so far as I limit myself by specific limitations in my claims, I illustrate in Figure 2 an inner axial passage or pipe 14 which extends through the center of the helix 13 and which contains any suitable resistance heater 15 connected by suitable conductive connections 15a and 15b to any suitable source of commercial current. The heater 15 may be controlled in its operation by any suitable heat responsive control means 16, shown in

40 45 50 Figure 2 as extending into any suitable pipe 16a extending through the end 11 of the cylinder and through several of the bends of the helix. Thus the operation of the heater 15 may be controlled by a suitable heat responsive element, which, in turn, responds to the temperature of the refrigerant adjacent its entry into the tortuous passage formed by the helix 13. Any suitable outside layer of insulation may be employed, as at 17.

55 60 65 It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic. For example, whereas I find the heat exchange unit shown to be highly advantageous, I may obtain my result by other heat exchange means. What is essential is that I provide means for heating the refrigerant, when necessary, as it is delivered from the compressor to the condenser. By controlling this heating effect in relation to or in response to variations in ambient temperature, I maintain an adequate uniformity of pressure conditions, and render it unnecessary to valve or to restrict the flow of the refrigerant to the condenser and to the receiver. Whereas the nature and position of the resistance 16 is adequate and practical, it will be realized that I may employ heat responsive means subjected to the movement of the refrigerant at any point

along its course. Whereas the temperature of the refrigerant is, in a broad sense, responsive to outside ambient temperature, I may, if I wish, employ heat responsive means directly subjected to variation in outside ambient temperature. In a broad sense, my invention contemplates varying the heat delivery in relation to or in direct or indirect response to changes in outside ambient temperature. Looking at the problem from a somewhat different angle, I may say that the function of the heat exchanger A in the circuit, as shown in Figure 1, is rather to prevent heat loss than to add heat, or to superheat. The problem solved by my invention is not that of affecting condenser pressure but, rather, that of preventing variations in ambient temperature from affecting condenser pressure. My heat exchanger A, controlled in response to variations in ambient temperature, adds temperature when necessary to prevent an unfavorable drop in condenser pressure. Whereas I have illustrated my invention as applied to control the flow of refrigerant from the discharge side of the compressor to the condenser, it will be understood that I may employ my invention at other points, where necessary, in the refrigerating circuit.

I claim:

1. The method of maintaining predetermined gas pressure in a refrigerating circuit, which includes sensing ambient temperature, and heating the refrigerant, as it passes from compressor to condenser, in controlled relation to variations of such ambient temperature.

2. The method of maintaining predetermined gas pressure in a refrigerating circuit, which includes heating the refrigerant, as it passes from compressor to condenser, and varying such heat input to the refrigerant, in response to variations of the ambient temperature of the space through which such refrigerant flows.

3. The method of maintaining predetermined hot gas pressure in a refrigerating circuit, which includes heating the refrigerant as it passes from compressor to condenser, and varying such heat input to the refrigerant in predetermined relation to variations of the ambient temperature of the space through which such refrigerant flows.

4. In combination, in a refrigerating system including a compressor, a condenser and an evaporator, a high pres-

sure discharge pipe extending from the compressor to the condenser, a pipe extending from the condenser to the evaporator and a return pipe extending from the evaporator to the suction side of the compressor, and means for maintaining the temperature of the hot gas delivered from the compressor to the condenser within a predetermined range, including heating means, and means for maintaining said heating means in heat exchange relationship with the hot gas flowing from the compressor to the condenser.

5. The structure of claim 4 characterized by and including a control element responsive to the temperature of hot gas.

6. The structure of claim 4 characterized by and including a tortuous passage means through which the hot gas flows on its way from the compressor to the condenser, heating means effective to deliver heat to the gas as it flows through the tortuous passage means, and heat-responsive means for controlling the operation of the heating means, said heating-responsive means being adapted to respond to the temperature of the hot gas flowing through the tortuous passage.

7. A method of operating a mechanical refrigerating circuit including a compressor, a condenser and an evaporator, in surroundings subjected to substantial variations in ambient temperature which includes sensing ambient temperature and supplying heat when needed, in controlled response to said sensing, to the refrigerant as it passes from compressor to condenser, effective to maintain a substantially uniform condenser pressure, and thereby preventing undesired condenser pressure drops which might otherwise be caused by undue reduction of the ambient temperature to which the refrigerating system is subjected.
